MAURITZ VOS AND HÅKAN KARL AUGUST STERKY, OF STOCKHOLM, SWEDEN, AS
SIGNORS TO TELEFONAKTIEBOLAGET L. M. ERICSSON, OF STOCKHOLM, SWEDEN, A
COMPANY OF SWEDEN

BAND FILTER

Application filed February 14, 1929, Serial No. 339,946, and in Sweden February 27, 1928.

The present invention relates to so called band filters which are used in telephone and high frequency systems to separate oscillations of different frequencies or different bands of frequencies. Especially in connection with multiple telephony or telegraphy, it often occurs that two or several band filters of different bands of frequencies have to be connected in parallel or in series in relation 5 to each other either on the input sides or on the output sides. In hitherto known simple band filters i. e. those consisting of a single section the characteristics of the two sides (i. e. the input and the output characteristic) are 10 similar so far as they are both falling or both rising on each side of the band of frequencies of the filter. In the former case the filter is not suitable for being connected in parallel because the characteristic of each of the filters 15 has low values for oscillations within the band of frequencies of the other filters the different filters connected in parallel thus forming short circuits for each other. Filters of the latter kind in which the characteristic is rising on both sides of the band of frequencies 20 are, on the other hand, not suitable for being connected in series because in this case each of the filters connected in series forms a very high impedance for oscillations within 25 the band of frequencies of the other filters. The object of the present invention is to bring about a simple band filter, which may be connected advantageously both in parallel and in series. The object of the invention is further to produce an efficacious filter of a design so simple as possible and to combine in such a simple filter all those qualities which are desirable in a band filter and which otherwise can be obtained only by comparatively 30 complicated devices.

The invention will be more closely described with reference to the attached drawings in which Figure 1 shows an embodiment of a single section filter. Figures 2 and 3 are 45 diagrams showing the variations of the input

and output characteristics of the filter according to Figure 1, as a function of the frequency. Figure 4 shows the connection of the filter according to Figure 1 to the anode side of an electron tube and Figure 5 the connection of said filter to the grid side of an electron tube. Figure 6 is a diagram showing the damping as a function of the frequency in the filter according to Figure 1. Figures 7 and 8 show different connections in cascade or in chain of sections according to Figure 1. Figures 9 and 10 show modifications of the single section filter according to Figure 1. Figures 11 and 12 show connections in series or in parallel respectively of 50 filters according to the invention.

The single section filter according to Figure 1 is composed of two inductively coupled inductances L_1 and L_2 and a condenser C_1 connected in parallel with L_1 and a condenser C_2 connected in series with L_2 . The input terminals 1 of the filter are formed by the terminals of the inductance L_1 which are connected to the condenser C_1 . The free end of the inductance L_2 and the outer pole of 55 the condenser C_2 form the output terminals 2 of the filter. By suitably selecting the ratio of transformation and the coupling coefficient k and by a corresponding dimensioning of 60 inductances and capacities the filter may be 65 adjusted to suit two impedances Z_1 and Z_2 (lines or apparatus) connected to the input and output terminals respectively in such a manner that oscillations within the desired 70 band of frequencies pass the filter without reflection losses. The impedances Z_1 and Z_2 which may be of different values in relation to each other may be assumed to have, at least approximately, purely real values of 75 impedance within the band of frequencies and especially for the geometric mean value of the two limiting frequencies f_1 , f_2 of the filter. Provided the filter is thus adjusted to predetermined values of Z_1 and Z_2 at the 80 geometric mean frequency between f_1 and f_2 85 90

and provided the losses in coils and condensers are negligible we obtain according to the general theory of the ideal artificial line with two input and two output terminals or the so called transducer (see for instance "Breisig, Theoretische Telegraphie", 2nd edition, page 401) the following formulas for a suitable dimensioning of the filter according to Figure 1.

$$C_1 = \frac{1}{2\pi Z_1} \times \frac{1}{f_1 - f_2}$$

$$L_1 = \frac{Z_1}{2\pi} \times \frac{f_1 - f_2}{f_1 \times f_2}$$

$$k = \frac{f_1 - f_2}{\sqrt{f_1^2 - f_1 f_2 + f_2^2}}$$

$$L_2 = \frac{Z_2}{2\pi} \times \frac{f_1^2 - f_1 f_2 + f_2^2}{f_1 f_2 (f_1 - f_2)}$$

$$C_2 = \frac{1}{2\pi \times Z_2} \times \frac{f_1 - f_2}{f_1 \times f_2}$$

An arrangement of the filter as described presents the following advantages:

A. As can be readily understood from the diagrams in Figures 2 and 3 which show the input and output characteristics of the filter drawn according to a symbolical method set forth by Zobel among others (The Bell System Technical Journal for January 1925, page 62) the filter may suitably be connected in series with other similar filters (having, however, different bands) on the input side 1—1 whereas the output side 2—2 may suitably be connected in parallel.

B. A filter section according to the invention has an impedance both on the input and the output side which is practically constant over the greater portion of the band of frequencies.

C. On account of the transformation within the filter said filter may be connected without reflection losses to two impedances of different sizes. The band width is then as can be seen by the third formula not dependent upon the ratio of transformation of the transformer and determined solely by the coupling coefficient k .

D. When connecting the filter section into the anode circuit of an amplifying tube according to Figure 4 the anode may be directly fed by continuous current over the coil L_1 without introducing a special choke coil in the supply lead and a blocking condenser or other coupling elements.

E. When connecting the filter section into the grid circuit in an audion tube it is usually desirable to dimension the side of the filter facing the grid for a high impedance i. e. to design the filter with a high ratio of transformation. The maximum attainable transformation ratio is then, however, limited by that the internal capacity of the inductance coil L_1 apparently reduces the value of L_1 . In the present filter one may, however, as-

sume that both the internal coil capacity and the grid circuit capacity are included in C_1 the filter thus functioning independently of otherwise disturbing internal coil capacity.

F. The filter section according to the invention is characterized by that the damping on both sides of the band of frequencies reaches very high values. The damping β as a function of the frequency is drawn symbolically in Figure 6. This diagram shows that the very good damping qualities of the filter makes it very suitable as a band filter.

There is no previously known filter in which all the abovementioned qualities may be combined.

In Figures 2 and 3 the dashed lines in the impedance diagrams represent purely imaginary values of the impedances (pure inductances and capacitances) whereas the unbroken portion of the impedance diagrams extending between the limiting frequencies f_1, f_2 in each of the figures represents purely real values (ohmic resistances).

In order to render the filter symmetrical the condenser C_2 connected in series with the inductance L_2 (Figure 1) may be divided into two condensers each having the capacity $2C_2$ which are connected into circuit according to Figure 9. In this way another embodiment of the invention is realized.

It is also possible to unite a number of filter sections according to the invention by means of cascade coupling resulting in circuit diagrams according to Figures 7 and 8. In such cases when two condensers are connected into circuit in parallel or in series by means of said cascade coupling they may, of course, be combined to one condenser having the double or the half capacity respectively.

Also other embodiments of the filter in addition to the above mentioned ones are conceivable such as for instance the substitution of the transformer L_1, L_2 by its equivalent circuit diagram according to Figure 10. Thus:

$$L_1' = L_1 - M$$

$$L_2' = L_2 - M$$

$$M = k \times \sqrt{L_1 L_2}$$

Figure 11 shows the realization of the connection in series of several filters having different band of frequencies. The connection in series is arranged according to the diagram on those sides where the parallel capacities C_1 are connected into circuit and where the characteristics according to Figure 2 are falling on both sides of the appertaining band of frequencies. Each of the filters connected in series offers thus only an insignificant impedance for oscillations within the band of frequencies of the other filters.

The connection in parallel of several filters is, on the other hand, realized according

to Figure 12 on those sides where the series capacities C_2 are connected into circuit. The different filters offer thus according to Figure 3 high impedance values for other oscillations than those lying within each of the appertaining band of frequencies.

We claim:

1. A band filter section consisting of two inductively coupled inductances (L_1, L_2), a capacity (C_1) connected in parallel with the one inductance (L_1) and a capacity (C_2) connected in series with the other inductance (L_2), the inductances and the capacities and the coupling coefficient (k) between the inductances being so dimensioned that substantially

$$C_1 = \frac{1}{2\pi Z_1} \frac{1}{f_1 - f_2}$$

$$L_1 = \frac{Z_1}{2\pi} \frac{f_1 - f_2}{f_1 \times f_2}$$

$$k = \frac{f_1 - f_2}{\sqrt{f_1^2 - f_1 f_2 + f_2^2}}$$

$$L_2 = \frac{Z_2}{2\pi} \frac{f_1^2 - f_1 f_2 + f_2^2}{f_1 f_2 (f_1 - f_2)}$$

$$C_2 = \frac{1}{2\pi Z_2} \frac{f_1 - f_2}{f_1 \times f_2}$$

f_1 and f_2 being the limiting frequencies and Z_1, Z_2 the terminal impedances, one of the two characteristics of the filter then falling on both sides of the band of frequencies and the other rising on both sides of said band.

2. A band filter as claimed in claim 1, connected to an apparatus with inner capacity, characterized by that said inner capacity is included in the parallel condenser of the filter.

3. A band filter as claimed in claim 1, characterized in that two or several sections having different band of frequencies are connected in series in relation to each other on those sides where their characteristics are falling on both sides of the corresponding band of frequencies whereas the opposite sides are connected to different impedances.

4. A band filter as claimed in claim 1, characterized in that two or several sections having different band of frequencies are connected in parallel in relation to each other on those sides where their characteristics are rising on both sides of the corresponding band of frequencies whereas the opposite sides are connected to different impedances.

In testimony whereof we affix our signatures.

MAURITZ VOS.

HÅKAN KARL AUGUST STERKY.
